DESIGN FOR A TEXTILE FABRIC OR SIMILAR ARTICLE

Marie Holm, Dobbs Ferry, N. Y., assignor to Carl Hellman, New York, N. Y.

Application March 9, 1936, Serial No. 61,528

Term of patent 3½ years

To all whom it may concern:

Be it known that I, Marie Holm, a citizen of the United States of America, residing at 40 Wall-grove Avenue, Dobbs Ferry, New York, have invented a new, original, and ornamental Design for a Textile Fabric or Similar Article, of which the following is a specification, reference being had to the accompanying drawing, forming a part thereof.

The figure is a plan view of a textile fabric showing my new design. The dot and dash lines on the drawing outline substantially a design unit, which unit is repeated in a relation wherein angle A corresponds to A' and B to B'.

I claim:

The ornamental design for a textile fabric or similar article as shown and described.

In testimony whereof I have signed this specification.

MARIE HOLM.
